UNITED STATES PATENT OFFICE.

JOBBY BELPEDIO, OF BRIDGEPORT, CONNECTICUT.

BROOM-SUPPORT.

1,197,252.

Specification of Letters Patent. Patented Sept. 5, 1916.

Application filed February 4, 1916. Serial No. 76,202.

To all whom it may concern:

Be it known that I, JOBBY BELPEDIO, a citizen of the United States, residing at Bridgeport, in the county of Fairfield and 5 State of Connecticut, have invented certain new and useful Improvements in Broom-Supports; and I do hereby declare the following to be a full, clear, and exact description of the invention, such as will enable 10 others skilled in the art to which it appertains to make and use the same.

The invention relates to improvements in broom supports.

The object of the present invention is to 15 improve the construction of broom supports or bridles and to provide a simple, practical and comparatively inexpensive device of strong and durable construction adapted to be readily applied to brooms of different 20 sizes and capable of adjustment upwardly and downwardly on the broom head to arrange it in proper position for supporting the same and to elevate it as the broom becomes worn or lower it should the straw of 25 the broom require compressing.

With these and other objects in view the invention consists in the construction and novel combination and arrangement of parts hereinafter fully described, illustrated in the 30 accompanying drawings and pointed out in the claims hereto appended, it being understood that various changes in the form, proportion and minor details of construction may be resorted to without departing from 35 the spirit or sacrificing any of the advantages of the invention.

In the drawing Figure 1 is a side elevation of a broom support constructed in accordance with this invention, Fig. 2 is a central 40 longitudinal sectional view, Fig. 3 is a plan view of the device, Fig. 4 is a detail view illustrating the construction of the expansible ring.

Like numerals of reference designate corresponding parts in the several figures of the drawing.

In the accompanying drawing in which is 50 illustrated the preferred embodiment of the invention, the broom support comprises in its construction a shell 1 designed to be constructed of sheet metal, leather, fiber, vulcanized rubber or any other suitable material and composed of upwardly tapered sides and connecting portions 2 located at 55 the side edges of the device and terminating short of the upper end of the sides of the

shell as clearly illustrated in Fig. 2 of the drawing. The sides of the shell conform to the configuration of an ordinary broom head and the projecting upper portions 3 have 60 curved edges and are approximately segmental. The shell which is adapted to be fitted on a broom head 4 as shown terminates short of the lower end of the broom head to expose the material thereof for sweeping 65 and it is adjustably secured to the said broom head by means of approximately vertical side bars or members 5 extending through transverse openings 6 in the upper portions of the sides of the shell and projecting above 70 the same and connected with the handle 7 of the broom by an expansible ring, 8. The side bars or members 5 are provided at their upper ends with eyes or openings 9 preferably formed by coiling or rolling the said 75 upper ends of the bars or members as clearly shown in Fig. 2 of the drawing and receiving the said ring 8. The ring 8 which is constructed of spring metal has overlapped terminal portions 10 and it is adapted to be 80 expanded to enable it to fit broom handles of different diameters.

The sides of the shell are provided at their upper portions with a plurality of slots arranged at intervals and adapted to 85 receive inwardly projecting spurs or prongs 12 carried by lower sections or portions 13 of the bars or members and adapted to be embedded in the broom head whereby the device is securely held in position. The lower 90 portions or sections 13 are connected by hinges 14 with the body portion of the bars or members and they are adapted to be swung inwardly and outwardly to engage them with and disengage them from the 95 broom head. When they are swung outwardly from the broom head the shell is free to be adjusted upwardly or downwardly. The spurs or prongs are designed to be of sufficient length to penetrate and 100 frictionally engage the broom head and be thereby retained in such engagement but any other suitable means may of course be employed for positively holding the hinged sections against outward movement. 105

It will be seen that the device is exceedingly simple and inexpensive in construction, that it is adapted to be readily applied to a broom head and is capable of vertical adjustment thereon and that the position of the device on the broom head may be easily and quickly changed when desired. Also it 110

will be clear that by its vertical adjustment it is adapted to fit broom heads of different sizes which may extend to a greater or less extent into the tapering shell.

What is claimed is:—

1. A device of the class described including an upwardly tapered shell composed of sides conforming to the configuration of an ordinary broom head and provided with 10 guiding means, bars or members slidable in the guiding means and provided at their lower portions with spurs or prongs adapted to be embedded in the broom head for securing the shell thereon and means for connecting the upper ends of the bars or members to a broom handle.
2. A device of the class described including a shell conforming to the configuration of an ordinary broom head and provided in 15 its upper portion with apertures forming guides and having a plurality of slots located at different elevations and side bars or members slidable in the guides and provided

with hinged lower sections having prongs or spurs adapted to extend through the said 25 slots to engage the broom head and secure the shell in different positions thereon.

3. A device of the class described including a shell conforming to the configuration of an ordinary broom head and provided 30 with slots arranged at different elevations, said shell being also provided with guiding means, side bars or members slidable in the guiding means and having hinged lower sections provided with spurs or projections 35 adapted to extend through the said slots to engage the broom head and an expansible ring adapted to slide on a broom handle and adjustably connecting the upper ends of the bars or members.

In testimony whereof I affix my signature in presence of two witnesses.

JOBBY BELPEDIO.
